UNITED STATES PATENT OFFICE.

JOSEPH L. HILLER, OF MATTAPoisETT, MASSACHUSETTS.

MAGNETIC SEPARATOR.

1,135,016.

Specification of Letters Patent. Patented Apr. 13, 1915.

Application filed December 24, 1909. Serial No. 534,818.

To all whom it may concern:

Be it known that I, JOSEPH L. HILLER, a citizen of the United States, residing at Mattapoisett, in the county of Plymouth and State of Massachusetts, have invented new and useful Improvements in Magnetic Separators, of which the following is a specification.

This invention relates to improvements in magnetic separators designed chiefly for use in separating from coal, on its way to a crusher or pulverizer, all hitchings, coupling pins, tramp-iron and other magnetic foreign substances which it is desired to prevent going into the machine with the coal, and which may be covered under the generic term magnetic material.

Heretofore in such apparatus the electromagnets which effect the separation have been arranged in fixed relation to the belt or other conveyer that carries the material to the crusher. When the magnets have accumulated a quantity of magnetic particles or bodies, it has been customary to stop the feed of material to the crusher and discharge such particles and bodies from the magnets, which stoppage of operations of feeding and crushing is objectionable and expensive.

It is one object of the present invention to obviate this, and to that end the invention consists in providing an electromagnet or electromagnets which are movable into active position to collect the magnetic material which may be present in the coal or other material to be crushed and into inactive or discharging position to discharge the collected magnetic material.

When the magnetic field is moved to discharging position, the energizing current will be broken or cut off, so that the collected material may be freely discharged. This cutting off of the current, and the reestablishment thereof when the magnets are moved or adjusted to operative collecting position, may be accomplished manually by a switch or automatically by providing the handle by which the magnets are shifted with means for breaking and establishing the current.

It is another object of the invention to facilitate the separation by agitating the material to so dispose the magnetic substances in the mass that there will be least interference with the magnetic action.

In the accompanying drawings illustrat-

ing the invention,—Figure 1 is a view, partly in elevation and partly in section, illustrating one embodiment of the invention. Fig. 2 is a detail showing the handle on the magnet axle for throwing the magnets into collecting and discharging positions, and showing conventionally, a switch for controlling the current of the magnets.

In the drawings, the reference numeral 1 designates a conveyer belt trained about drums 2, 3, and adapted to carry the material to be crushed on its way to a crushing machine. If desired, the drum 3 at the discharge end of the conveyer belt may be magnetic to attract to the conveyer magnetic substances which it is desired to separate out of the material going to the machine, and in that event a catcher 4 is disposed beneath the conveyer belt into which the material attracted by the magnetic belt-drum drops after passing out of the magnetic zone of the drum; and is conveyed away to any suitable depository or place. Arranged at a suitable point in the travel of the material on its way to the crushing machine I provide an electromagnet 5, or preferably a series of electromagnets, to collect the magnetic substances that may be present in the material to be crushed, and which it is desired to separate therefrom. Such magnet or magnets may, as shown in Fig. 1, be arranged to collect the magnetic substances as the material leaves the conveyer or belt, in which event each electromagnet may have a duplex collecting pole or surface 5^a, 5^b in stepped relation, so that should magnetic material, for any reason, not be held by the one collecting pole or surface, it will be attracted and collected by the other pole or surface. In each instance, however, the electromagnet or magnets are movably mounted so that they may be moved into active or collecting position or into inactive or discharging position. As shown the magnets are carried by a rotating or rocking shaft 6 arranged in juxtaposition to a discharging slide 7, so that by rotation of said shaft the magnets may be brought into active position to collect the magnetic material, as illustrated in full lines, and when material has accumulated upon the magnet or magnets making it desirable to discharge the same therefrom, said magnet or magnets may be rotated to the position illustrated in dotted lines to discharge the collected material onto the slide. This may be done very

quickly, so that there is little liability of any undesirable magnetic material passing the zone of the magnets during the operation of discharging, and, if desired, the arrangement of magnets could be duplicated to take care of any such contingency.

As before stated, when the magnets are moved to discharging position the energizing current is cut off so that the collected particles are free to immediately leave the magnets and fall into the slide. This may be accomplished by a switch shown conventionally at 8, Fig. 2, or in any other suitable way within the skill and knowledge of electricians.

During the time the magnets are in the position shown in dotted lines in Fig. 1 and the energizing current thereof cut out to discharge the magnetic material therefrom, the material discharged from the conveyer 1 may be deflected and directed with certainty into the chute 15 and prevented from going with the magnetic material into the chute 7. This may be conveniently accomplished by a pivoted deflector 16, Fig. 1, controlled by an operating handle 17. As shown in this figure, the deflector is arranged so that the magnets may attract magnetic material thereto. When this material is to be dumped, the deflector is moved inward to guide the material into the chute 15.

Movement of the magnets into inactive or discharging position may be accomplished in any desired manner. As illustrated the magnets are arranged upon a rotatable or rocking shaft 6, to the end of which a suitable operating handle 9 may be secured. In Fig. 2 is illustrated such an operating handle working over a quadrant 10 provided with a notch into which a locking dog 11 carried by the handle engages when the magnets are in collecting position. The current for the magnets may be taken in any suitable way, for example, as shown conventionally in Fig. 2, by collectors or brushes 12.

As shown in Fig. 2, the magnet shaft 6, may be carried in movable slides 13, so that the magnets may be adjusted to a position with relation to the path of the material to secure best results under varying circumstances.

To facilitate the separation of the magnetic material, the mass of material on the conveyer may be agitated by means of agitating fingers 18 carried by rock shafts 19, the ends of said fingers projecting into the path of the material on the conveyer 1, agi-

tating the same to allow the magnetic material which is of greater specific gravity to find its way to the bottom of the mass, and thus be in best position for the magnetic attraction of the drum 3. These fingers are preferably arranged in a plurality of series, those on one shaft being in staggered relation with like fingers on the next adjacent shaft, said shafts having affixed to their ends arms 20, the free ends of which are connected by springs 21 to the frame-work of the machine, by which the agitating fingers are yieldingly held to their work.

22 designates a spreader carried by independently yieldable hangers 23 which are movable in brackets 24 and surrounded by spring 25 bearing against nuts on the hangers and said brackets. This spreader serves to evenly dispose or lay the material on the conveyor.

Having thus described the invention what is claimed is,—

1. In a magnetic separator, an electro-magnet a conveyer for delivering material to be separated directly on to the poles of said electro-magnet, means for moving said electro-magnet into the path of the material discharged from said conveyer to collect magnetic material therefrom, and out of said path to discharge the magnetic material from the poles to said magnet, and movable means for deflecting material delivered by said conveyer away from the electro-magnet when the latter is in its discharging position.

2. A magnetic separator comprising stationary magnets having upwardly disposed adjoining inclined magnetic collecting surfaces, means for directing material to be operated upon to the uppermost of said surfaces and permitting it to fall thereon by gravity, means for receiving such other material as passes over the collecting surfaces of said magnets, means for receiving the material collected on said surfaces, means for moving said magnets away from the flow of said material for discharging the magnetic substances collected thereon, and means for breaking the electric circuit through said magnets when moved to discharging position.

In testimony whereof I have hereunto set my hand in presence of two subscribing witnesses.

JOSEPH L. HILLER.
